RAIL-CROSSING STRUCTURE

Application filed January 15, 1930. Serial No. 420,947.

This invention relates to railroad crossings and especially to crossings of the rigid or cast type.

There are two main types of rail crossings in general use, to-wit, the built-up type and the rigid or cast type.

The built-up type has certain advantages such as presenting a rolled rail surface to the pounding and wear of the rolling stock passing over the same but it has certain disadvantages and they are the bolting together and fitting of numerous parts and lack of rigidity.

Cast crossings also have advantages such as great rigidity and strength but they require the use of high grade steels, such as manganese steel, etc., which gives considerable trouble during the casting operation due to the enormous shrinkage which is encountered in cooling, this shrinkage causing cracking and porous spots etc. which develop weaknesses and breakage when the crossings are placed in operation.

The object of the present invention is to construct a crossing combining the advantages of both types; first, by employing a casting which permits the use of any commercial cast steel; secondly, by presenting a continuous rolled rail steel surface to the wheels of the rolling stock; and third, by providing a crossing which has greater rigidity and strength than either the built-up or solid cast type now in use.

The rail crossing is shown by way of illustration in the accompanying drawings, in which—

Fig. 1 is a plan view of a complete crossing,

Fig. 2 is a perspective view of one of the intersecting parts of the crossing, said view showing the wearing block inserted and in position,

Fig. 3 is a vertical cross section taken on line III—III of Fig. 2,

Fig. 4 is a perspective view of one of the clamping guard plates, said plate also functioning as a wheel flange guide.

Referring to the drawings in detail and particularly Fig. 1, it will be noted that the crossing consists of four arms generally indicated at 1, 2, 3 and 4. These arms intersect

each other at the points indicated at A, B, C and D and they are extended beyond the points of intersection as indicated at 1^a, 2^a, 3^a and 4^a so as to permit the main line rails indicated at 5, 6, 7, and 8 to be bolted thereto. 55

Pockets are formed at the points of intersection indicated at A, B, C and D and wearing blocks such as indicated at 9 are inserted in each pocket. The surface of each block is provided with flange grooves such as shown at 10 and they are slotted as shown at 11, see Fig. 3, to permit wedges 12 to be driven therethrough. The walls of the respective pockets are also slotted to permit the wedges to extend completely through as shown in 65 Figs. 1 and 3 and to permit insertion of auxiliary wedges such as shown at 13 and 14.

Each arm of the casting is provided with a base plate 15 which extends from end to end of the arms and beneath the intersecting points indicated at A, B, C and D, thus forming a rigid base for the several connected arms and the extensions thereof and at the same time forming a bottom section for the pockets in which the wearing blocks are inserted. The wearing blocks, by the way, are heavy as they extend from the top surface of the rails to the bottom thereof so as to be supported by the base plates 15, their weight being so great that they might be termed anvil 80 blocks. Spelter such as shown at 16 is poured around the blocks when they are inserted so as to form a resilient cushion and to secure them rigidly when they are in position, the main securing means, however, being the 85 wedges 12, 13 and 14. Due to the considerable weight presented by each wearing block, the pounding of the wheels when jumping the flange grooves is absorbed without transmitting much vibration to the casting. It may further be stated that these blocks are prefer-

ably made of heat treated alloy steel, such as chromium steel, or the like, thus presenting a surface which can withstand the pounding and wear of the wheels passing over the same. 90

It should also be noted that each wearing block is provided with four lug-like projections such as shown at 9^a, 9^b, 9^c and 9^d. The main line rails indicated at 5, 6, 7 and 9 abut the lugs 9^a and 9^b and the intermediate rolled 100

rails such as shown at 5^a, 6^a, 7^a and 8^a abut the inner lugs indicated at 9^c and 9^d. The several rolled rails together with the wearing blocks thus present a continuous steel surface over which the wheels of the rolling stock pass thereby providing a surface which can stand the pounding and wear and tear of the rolling stock passing over the same. The main line rails, 5, 6, 7 and 8 are secured to the outer ends of the arms indicated at 1^a, 2^a, 3^a and 4^a and are further secured by clamping guard plates such as shown at 1^b, 2^b, 3^b and 4^b by means of bolts extending through the rails, the arms and the clamping plates as indicated at 18. The intermediate rails 5^a, 6^a, 7^a and 8^a are bolted to the arms 1, 2, 3 and 4 as indicated at 19 and they are supported throughout their length by the base plates 15. The ends of the main line rails shown at 5, 6, 7 and 8 are also supported by the base plates 15, hence both the intermediate and main line rails are rigidly supported and secured with relation to the casting forming the crossing, thus eliminating any working or play between the rail sections and the wearing blocks when the rolling stock is passing over the same. The clamping plates shown at 1^b, 2^b, 3^b and 4^b are provided with wheel flange guides as shown at 20 and the intermediate rails 5^a, 6^a, 7^a and 8^a may similarly be provided with wheel flange guides as shown at 21, thus insuring a continuous wheel flange guide while the wheels of the rolling stock are passing over the crossing. The casting forming the crossing may in this instance be cast from practically any grade of commercial cast steel, thus reducing shrinkage troubles and warping to the minimum. High grade and hard steel can be eliminated as the rolling stock does not come in contact therewith at any point. The insertion and the rigid bolting of the intermediate rolled rail sections shown at 5^a, 6^a, 7^a and 8^a is important; first, because in unison with the wearing blocks and the main line rails they present a continuous steel surface to the wear and tear of the rolling stock passing over the same; and they furthermore, reinforce and strengthen the arms 1, 2, 3 and 4 of the casting, thus eliminating all danger even though one or more of the arms should crack. Again the intermediate rolled rail sections function as brace members and to that extent increase the rigidity of the crossing as a whole. While certain features of the present invention are more or less specifically described, I wish it understood that various changes may be resorted to within the scope of the appended claims. Similarly, that the materials and finishes of the several parts employed may be such as the manufacturer may decide, or varying conditions or uses may demand. Having thus described my invention, what

I claim and desire to secure by Letters Patent is—

1. A rail crossing comprising four integrally cast arms, said arms forming four points of intersection and being extended beyond the points of intersection, a plurality of pockets formed in the casting, one at each point of intersection, a steel wearing block secured in each pocket, rails secured to the arms of the casting at points intermediate the wearing blocks and abutting the same, and rails secured to the outer ends of the arms and also abutting the wearing blocks. 70

2. A rail crossing comprising four integrally cast arms, said arms forming four points of intersection and being extended beyond the points of intersection, a plurality of pockets formed in the casting, one at each point of intersection, a steel wearing block secured in each pocket, rails secured to the arms of the casting at points intermediate the wearing blocks and abutting the same, and rails secured to the outer ends of the arms and also abutting the wearing blocks, said rails and wearing blocks presenting a continuous steel surface for the wheels of rolling stock passing over the crossing. 80

3. A rail crossing comprising four integrally cast arms, said arms forming four points of intersection and being extended beyond the points of intersection, a plurality of pockets formed in the casting, one at each point of intersection, a steel wearing block secured in each pocket, rails secured to the arms of the casting at points intermediate the wearing blocks and abutting the same, rails secured to the outer ends of the arms and also abutting the wearing blocks, and a base plate formed integral with each arm and with each other and extending underneath the wearing blocks. 95

4. A rail crossing comprising four integrally cast arms, said arms forming four points of intersection and being extended beyond the points of intersection, a plurality of pockets formed in the casting, one at each point of intersection, a steel wearing block secured in each pocket, rails secured to the arms of the casting at points intermediate the wearing blocks and abutting the same, rails secured to the outer ends of the arms and also abutting the wearing blocks, said rails and wearing blocks presenting a continuous steel surface for the wheels of rolling stock passing over the crossing, and clamping plates 100 cooperating with the outer ends of the arms to secure the last named rails to the outer ends of the arms. 110

5. A rail crossing comprising four integrally connected arms, said arms forming four points of intersection and being extended beyond the points of intersection, a base member forming a part of each arm and extending from end to end thereof, said base members being also integrally connected, a 125

plurality of wearing blocks secured to the arms and their base members, one block at each point of intersection, rails secured to the arms and supported by the base members thereof at points intermediate the wearing blocks and abutting the same, and rails secured to the outer ends of the arms and supported by the base sections thereof and also abutting the wearing blocks, said first and last named rails together with the wearing blocks forming a steel surface for the wear and tear of rolling stock passing over the same, and the arms together with the base members forming a support for said steel surface.
